UNITED STATES PATENT OFFICE.

EDWARD J. BARCALO, OF BUFFALO, NEW YORK.

DESIGN FOR A BEDSTEAD.

SPECIFICATION forming part of Design No. 35,528, dated December 31, 1901.

Application filed December 6, 1901. Serial No. 84,969. Term of patent 7 years.

To all whom it may concern:

Be it known that I, EDWARD J. BARCALO, a citizen of the United States, residing at Buffalo, in the county of Erie and State of New York, have invented and produced a new and original Design for Bedsteads, of which the following is a specification, reference being had to the accompanying drawing, forming a part thereof.

10 The figure in the drawing is a perspective view of a bedstead, showing the design.

As shown in the drawing, the bedstead comprises a headpiece A, a footpiece B, and side rails C and D, which are arranged between 15 and connect the sides of the head and foot pieces.

E E' represent a pair of brackets secured to and depending from one side rail intermediate of its ends, and F F' represent a pair 20 of brackets similarly secured to and depending from the other side rail, the brackets of one pair being arranged opposite to the brack-

ets of the other pair. The lower ends of the opposite brackets are connected by horizontal bars or rails G, which extend transversely 25 beneath the side rails of the bedstead parallel with each other. The transverse bars G are shown to be connected to each other by longitudinal horizontal bars H.

The material or leading feature of the design consists in the side rails of the bedstead having intermediate of their ends depending brackets, the brackets of one side rail being connected to the brackets of the other side rail by parallel transverse rails. 30

What I claim is—

35 The design for a bedstead substantially as herein shown and described.

Witness my hand this 4th day of December, 1901.

EDWARD J. BARCALO.
